UNITED STATES PATENT OFFICE.

HENRY CAPEL LOFFT HOLDEN, OF BLACKHEATH, LONDON, ENGLAND.

WHEEL FOR VEHICLES.

Application filed January 3, 1924. Serial No. 684,194.

To all whom it may concern:

Be it known that I, HENRY CAPEL LOFFT HOLDEN, a subject of the King of England, residing at Blackheath, London, England, have invented new and useful Improvements in Wheels for Vehicles, of which the following is a specification.

This invention relates to improved means for securing a road tire upon a flanged railway wheel, so that such a wheel can be used either on the railway or on the road.

For this purpose I employ upon a flanged railway wheel, a transversely split or divided ring (having ends which can be closed together or separated) which when being inserted in position rides up the tapered tread of the railway wheel towards the flange of the latter.

The present invention is characterized by the use in combination with the flanged railway wheel, of a transversely divided or split ring formed in one or more lengths and of wedge or tapered cross section, so that as an intermediate member it can be forced up the tread of the wheel and towards the flange, for the purpose of abutting at its exterior surface against the inside of the road-tire base, the latter being arranged radially outside said tread. This intermediate member is maintained upon the tread of the wheel between the flange of the railway wheel and a retaining device carried by the wheel, such as an L-shaped bolt bearing against the edge of the intermediate member.

The invention is hereafter described with reference to the annexed drawings, in which:—

Figure 1 is a cross section of one form of carrying out the invention.

Figure 2 is a similar view of another form.

Figure 3 is a part side elevation of Figure 2 seen from the left.

Figure 4 is a part side elevation of Figure 2 seen from the right but with a longer bolt head.

Figure 5 is a side elevation showing a clip or locking piece in place.

Figure 6 is a diagram showing the transversely divided ring formed in two pieces.

Figure 7 shows a screw-threaded bolt for starting the ring from the tapered tread of the wheel.

Figure 8 shows a peg whereby the ring may be forced off the tread of the wheel.

Referring to Figure 1, I fit the railway wheel *a* which as usual is provided with an outwardly directed flange *b* to engage the inner edge of the rail of the track, with a transversely split or divided ring *c*, which ring is tapered and adapted to embrace the periphery *a*¹ of the wheel *a* and at the same time to afford a cylindrical outer bearing surface. This split ring *c* is shown appropriately tapered or coned on its inner periphery, to ride up the coned metal tread *a*¹ of the railway wheel. This divided ring may be formed in one length, as will be understood from Figure 5, or in more than one length as shown diagrammatically in Figure 6.

The divided ring *c* is detachably held in position on the metal tread of the wheel by retaining devices such as L-shaped holding clips *e* *e*¹ the arm *e*¹ of which engages the outer edge of the split ring *c*, that is the edge remote from the flange *b* on the wheel *a*, and the longer arm *e* of which clip is adapted to be drawn towards the central plane of the wheel *a*; this may be effected by screw-threading the second arm *e*, passing it through a lug *f* on the inner face of wheel periphery *a*¹ and fitting it with a nut *e*². The arm *e* may alternatively be passed through the web of the wheel *a*, as will be obvious.

In this way, the clips *e* *e*¹ retain the split ring *c* upon the wheel *a* and can be operated to cause it to ride up the coned tread *a*¹ of the wheel periphery towards the outwardly directed flange *b*, when required. Any desired number of these retaining clips *e* *e*¹ may be employed at intervals around the wheel *a*, and it will be noted that they are arranged at the side of the wheel *a* opposite to the flange *b*.

Before the transversely divided and tapered ring *c* is expanded by movement up the coned periphery *a*¹, the carrier base or rim *g* for a road tire *e. g.* the resilient tire *g*¹, is fitted around and outside the intermediate member *c*. This tire carrier or base *g* may consist of the usual metal ring or felly on which an ordinary rubber, road-wheel tire is mounted, or it may be, for instance, a beaded-edge rim of the usual clincher type for a pneumatic tire, as will be obvious.

The intermediate and transversely divided member *c* when drawn or otherwise forced up the coned periphery *a*¹ of the railway wheel, expands and makes locking contact with the inner periphery of the tire base *g* and also with the outer periphery *a*² of the wheel, so as to hold the parts together. When so expanded by its movement transversely across the tread *a*⁴ of the wheel *a* it affords an almost continuous cylindrical outer surface which bears against the inner periphery of the carrier *g* for the resilient tire.

If desired, and as shown in Figure 6, the intermediate member *c* may be formed in a plurality of lengths i. e. in segments, means being also provided for forcing each such length or segment up the coned tread *a*¹ and retaining it in its operative position.

The arrangement shown in Figures 2, 3 and 4 shows the application of the present invention to one of the well known cast-steel railway wheels, which by way of example may be supposed to have been previously fitted to a road lorry or truck, so that the road truck fitted with such wheels can be driven along railway lines. The transversely divided wedge-ring *c* which forms the intermediate member or adapter is here shown engaged at its edge remote from the flange *b*, by the cranked head *h*¹ of a bolt *h* which forms one of the retaining devices and passes transversely through the wheel *a*, the nut *h*² for the bolt *h* being seated in a lateral recess or socket *i* formed in the wheel *a*. By tightening up the nut *h*², the head *h*¹ which is seated in a corresponding slot *i*¹ in the opposite lateral face of the wheel *a*, causes the transversely split ring *c* to ride up the coned periphery *a*¹ and it also prevents the said split ring *c* from laterally moving backwards to such an extent as to pass off the wheel periphery. Any desired number of these retaining bolts *h* *h*¹ may be employed, e. g. 4 to 8, arranged at intervals around the tread of the wheel, depending upon the size of the wheel.

If desired, for two or more of the bolts and as will be understood from Figure 4, the head *h*¹ may be of such a length that it extends to the top of the tire base *g*, so as to prevent that also from moving laterally away from the flange *b*. Thus a self-propelled road vehicle which has been fitted with flanged wheels whereby it is adapted to be driven on railway lines, can without difficulty be provided with a rubber tire for use on ordinary roads or similar surfaces, and it is to be noted that there are no projections from the railway wheel beyond the sides of the wheel.

In Figure 5, I show another similar device for preventing the tire base *g* from moving laterally; in this arrangement a plate *j* is bolted or otherwise secured to the trans-

versely divided ring *c* and projects to the top of the tire base *g* so that a number of these plates *j* at intervals can be employed to maintain the tire base in position upon the ring *c* and therefore upon the wheel *a*.

It is to be understood that any suitable form of resilient tire can be mounted on the tire base *g* which latter is maintained in position by the radially-outwards expansion or wedging action of the divided ring *c* as it is being forced up the coned tread *a*¹. For convenience a solid rubber tire has been shown at *g*¹.

To facilitate the removal of the transversely divided ring *c* and rubber tire base *g* when required, I show a hole in the rail-flange *b* of the railway wheel through which pressure can be applied to the side or edge of the divided ring *c*, after the holding clips *e* *e*¹ or bolts *h* have been removed or slackened. For example, by providing screw-threaded holes as *k*, Figure 1, through the flange *b* at three or more points, suitable set-screws or bolts *k*² can be employed to start the tapered and divided ring *c* back along the coned periphery *a*¹ of the wheel, so that the base *g* and the rubber tire *g*¹ can be freed and removed.

In Figures 2, 3 and 8, a plain hole *k*¹ is shown through which a peg, bar or drift *k*² can be inserted.

The gap in the transversely divided or split ring *c* is shown at *c*¹ in Figure 5 and with a taper in the tread *a*⁴ of 1 in 20; the ends of the split ring *c* might be arranged to be close together when the intermediate member *c* was half-way up the coned periphery *a*¹.

The present improvement enables an automobile vehicle which has been fitted with flanged railway wheels whereby it can be used on the rails of a railway track, to be quickly and economically fitted with means whereby the same wheels of the vehicle can be employed upon the highway.

Having now particularly described and ascertained the nature of my said invention and in what manner the same is to be performed, I declare that what I claim is:—

1. In a wheel for use on either road or rail, the combination of a wheel with a coned tread, a lateral guiding flange to said wheel tread, a road-tire arranged radially outside said wheel tread, a transversely divided ring adapted to be mounted on said tread, said ring being tapered in cross section and arranged as an intermediate locking member between said wheel tread and said road tire, and means for retaining the intermediate ring upon the wheel tread.

2. In a wheel for use on either road or rail, the combination of a wheel with a coned tread, a rail-engaging flange carried by a said wheel, a road-tire arranged radially outside said wheel tread, a transversely

divided ring adapted to be mounted on said wheel tread, said ring being tapered in cross section and arranged between said tread and said road-tire, and detachable means carried by the wheel for retaining the intermediate ring upon the wheel tread.

3. In a wheel for use on either road or rail, the combination of a wheel with a coned tread, a rail-engaging flange carried by said wheel, a road tire mounted on a base and arranged radially outside said wheel tread, a transversely divided ring adapted to be mounted on said wheel tread, said ring being tapered on its inner periphery to conform with the coned tread of the wheel and to afford an approximately cylindrical outer bearing surface, said ring being adapted to be expanded when forced up the coned tread of the wheel, said ring being adapted to lock the tire base to the wheel tread, and means for retaining the divided ring in its locking position.

4. In a wheel of the type described, the combination with a flanged railway wheel, of a resilient tire for use on the road, a base for said road tire, a transversely divided ring adapted to be introduced between said tire base and the tread of said flanged railway wheel, and of detachable means carried by the railway wheel for retaining the ring in position.

5. In a wheel of the character described, a laterally flanged railway wheel, a road tire, a base for said road tire, a transversely divided and expansible ring adapted to be mounted on the tread of the railway wheel from the side opposite to the said flange, and means for forcing said expansible ring across the tread of said wheel, said means also serving to retain the ring upon the wheel.

6. In a wheel of the character described, a railway wheel having a lateral rail-engaging flange, a road tire, a carrier base for said road tire, said tire and its carrier being arranged radially outside the tread of the railway wheel, a transversely divided and expansible ring adapted to be mounted on the tread of the railway wheel from the side opposite to said flange, and means carried by the wheel for forcing said expansible ring across the tread of said wheel until the exterior of said ring abuts against the interior of the said carrier-base, said means also serving to retain the ring in operative position.

7. In a wheel of the character described, a railway wheel having a lateral rail-engaging

flange, a road tire, a carrier-base for said road tire, said carrier-base and tire being arranged radially outside the tread of the said wheel, a transversely divided and expansible ring adapted to be mounted on the tread of the wheel from the side opposite to the aforesaid flange, said ring being tapered in cross section and forming an intermediate locking member between said tread and its carrier-base, and means carried upon the wheel for retaining the ring in its expanded and locking position.

8. The combination with a laterally-flanged railway wheel, of a resilient tire, a carrier for said tire, said tire and its carrier being arranged radially outside the tread of said wheel, a transversely divided locking ring adapted to be inserted between said tread and said tire-carrier from the side of the wheel opposite to the lateral flange of the wheel, said ring being tapered in cross section so that as it moves across the tread of the wheel it will bind against the interior periphery of the tire carrier, lateral slots in said wheel on the side opposite to the flange, and L-shaped bolts carried by the wheel, said bolts having their cranked ends arranged in said slots and bearing against the edge of the locking ring remote from the flange upon the wheel.

9. In a wheel of the character described, a laterally flanged railway wheel, a resilient tire for use on the road, a carrier for said road-tire, a transversely divided locking ring between said tread and said carrier, said ring being tapered in cross section and inserted from the side of the wheel opposite to the lateral flange of said wheel, slots in the side of the wheel opposite to the lateral flange, and L-shaped retaining bolts carried by the wheel, said bolts having their cranked heads arranged in said slots and adapted to bear against the edge of the locking ring remote from the flange upon the wheel, the cranked heads of said bolts also bearing against the road-tire carrier.

10. In a wheel of the character described, a laterally flanged railway wheel, a road tire, a carrier-base for said tire, a transversely divided ring inserted between the tread of said wheel and said carrier base from the side of the wheel opposite to the flange, and passages through the lateral flange to afford access to the transversely divided ring.

In testimony whereof I have signed my name to this specification.

HENRY CAPEL LOFFT HOLDEN.
